UNITED STATES PATENT OFFICE.

BENJAMIN DAVIES, OF BROOKLYN, ASSIGNOR TO L. STRAUS & SONS, OF NEW YORK, N. Y.

DESIGN FOR THE ORNAMENTATION OF GLASS VESSELS.

SPECIFICATION forming part of Design No. 23,253, dated May 8, 1894.

Application filed April 5, 1894. Serial No. 506,506. Term of patent 7 years.

To all whom it may concern:

Be it known that I, BENJAMIN DAVIES, of Brooklyn, in the county of Kings and State of New York, have invented and produced a new and original Design for the Ornamentation of Glass Vessels, of which the following is a specification, reference being had to the accompanying drawings, in which—

Figure 1—is a plan view of a dish ornamented with my design, and Fig. 2—represents a cross sectional view of the same.

The leading feature of my design consists of a continuous groove forming a scroll around the vessel, the loops of the scroll and the central space having smaller patterns.

In the design as represented in the accompanying drawings, the continuous groove A crosses itself repeatedly to form a series of nearly circular loops around the vessel, each

of which loops contains a pattern or figure *a* 20 of generally finer grooves. The pattern produced by the groove A leaves a central star-shaped space which is occupied by a group or figure *b* comprising two crossed triangles and a small conventional star. And the 25 spaces between the outer curves of the loops are occupied by fan figures *c*.

Having thus described my invention, what I claim is—

The design for the ornamentation of glass 30 vessels, substantially as herein shown and described.

In testimony whereof I affix my signature in the presence of two subscribing witnesses.

BENJAMIN DAVIES.
